UNITED STATES PATENT OFFICE.

CHARLES G. CORNELL, JR., OF NEW YORK, N. Y.

FORMING DIE.

1,420,970.

Specification of Letters Patent. Patented June 27, 1922.

Application filed August 1, 1921. Serial No. 483,843.

To all whom it may concern:

Be it known that I, CHARLES G. CORNELL, Jr., a citizen of the United States, and a resident of New York, in the county of New York and State of New York, have invented a new and Improved Forming Die, of which the following is a specification.

This invention relates to a forming die for flanging the ends of pipes and more especially to the parts of a plunger or follower of the male member which cooperates with the female member of a die for progressively carrying out a series of steps or treatment of the end of an iron, steel or other metal pipe to produce a flanged end thereon.

The object of the invention is to provide means whereby two forming faces of the male member of the die can be successively and quickly presented to the end of the pipe desired to be flanged and the steps can be continuously and expeditiously carried out on pipe ends of large as well as small diameter and without injury to said forming faces or effecting the efficient operation of the die or the high quality of work produced.

The invention consists of structural characteristics and relative arrangements of elements which will be hereinafter more fully described and particularly pointed out in the appended claims.

In the one sheet of drawings in which similar reference characters indicate the same parts in the several figures,

Figure 1 is a top plan view of the separable female member of the die;

Figure 2 is a side elevation of said separable die;

Figure 3 is a section on line III—III of Figure 2 with an upper end of a pipe to be flanged in place;

Figure 4 is a sectional view similar to Figure 3 showing the improved plunger or follower of the male member of the die carrying out the first step of flanging a pipe end; and

Figure 5 is a view similar to Figure 4, showing the plunger or follower completing the flanging of a pipe end;

In the drawings, 10, 11, represent the two sections or halves of the female member which are preferably hinged together by two pairs of perforated lugs 12 and 13, and a pin 14, as will be readily understood.

The opposite sides of the two halves or sections 10, 11 are provided with perforated lugs 15 and 16 adapted to be engaged by a removable pin 17 for the purpose of securely holding said sections 10, 11, about the end of a pipe, as shown in Figure 3, and at the same time permitting the pipe end to be readily removed after the flanging operation, to be presently described, are completed.

The inner portions of the sections 10 and 11 are so formed, constructed and arranged that when locked together or in their closed position, as indicated, they form an axial cylindrical hole 18 having a bore of substantially the same diameter as the outside diameter of the pipe which is to be flanged, while in the upper ends of the sections 10 and 11 in their closed position is formed a cylindrical recess 19 of a diameter equal to the diameter of the flange to be produced for reasons which will be more clearly understood from the disclosure of the cooperating parts to be presently given. The foregoing type of female member of a die with the bore or hole 18 combined with a recess 19 is common and well known and I make no broad claim for this form of construction.

20 is the male member of the die, follower or plunger which may be mounted and operated or reciprocated by any suitable mechanism with respect to the stationary die sections 10 and 11, as is common in horizontal or other forms of hydraulic presses or similar classes of machines and needs no further showing or disclosure. Said follower or plunger 20 is provided with two rigid and firm cylindrical extensions 21 and 22 arranged with their axes in alignment, and extension 21 is of such a depth and diameter as to fit within the recess 19 in the female sections 10 and 11 of the die, while the smaller section 22 is of a diameter equal to the inside diameter of the pipe to be flanged as illustrated in Figure 4.

23 is a removable and rotatable swivel ring 100 preferably frusto-conical in shape and is so proportioned and constructed as to be provided with an axial and cylindrical hole 24 of a slightly larger diameter than the diameter of the extension 22 so as to permit said swivel ring 23 to be removable and capable of rotary motion about and independent of the extension 22 if necessitated during the

pipe flanging operations. The base and the height of the ring 23 are slightly smaller than the diameter and depth of the recess 19, as will be clearly understood by reference to 5 Figure 4.

The parts being constructed and arranged as shown, the manner of using the invention is as follows:

The sections 10 and 11 of the female member having been opened up and the end of the pipe P, having been preferably and previously heated to a bright red heat, is inserted in said female member, so that the end F of the pipe P, assumes the position shown 15 in Figure 3. The sections 10 and 11 of the female member are then locked together in the position shown in Figs. 1 and 2. The male member with its section 21 and extension 22 and the removable swivel ring 23 applied and adjusted to the position shown 20 in Fig. 4 is then moved by any suitable and sufficient pressure to cause the extension 22 to first enter into the end F of the pipe end and upon further movement into the 25 female member until the forward or outer reduced portion of the swivel ring 23 engages the inner edge of the open pipe end, and on continued progress of said extension 22 into the pipe end, the swivel ring 23 will 30 cause the end F of the pipe to expand and flare outwardly and when the outer or reduced portion of the ring 23 engages or abuts against the inner edge or circular portion of smallest diameter of the flaring end 35 of the pipe, as shown in Figure 4, the male portion with its sections 21 and 22 and ring 23 are removed from the female section of the die and after the end of the extension 22 sufficiently clears the female member sections 10 and 11, the swivel ring 23 is moved 40 along and slipped from the extension 22 by any suitable means and put aside for operating on the next pipe section. After the ring 23 has been removed, as just explained, the male member of the die is again introduced into the previously flared pipe end F and forced into the female member and inner straight section of the pipe until the section 21 and extension 22 45 assume the positions shown in Fig. 5, when the flanging of the pipe is completed.

The male member of die is then removed from the flanged end of the pipe when the female member of the die is opened up and 55 the flanged pipe removed when the forming die is ready for a repetition of the steps just described.

If it is found that the pipe end during the flanging is not pliable and readily responsive to the male member of the die, the end of the pipe may be reheated if found necessary as is common in this class of operations.

It will be seen that the separate and independent ring 23 acts as a swivel which helps

the parts of the pipe end and forming die to remain in axial alignment while the flanging operations are being carried out.

From the foregoing disclosure of the construction and arrangement of the improvement and mode of applying the same, it will be seen that all the objects and advantages recited in the statement of invention have been fully and efficiently carried out, and while I have shown and described 70 my preferred form of the forming die, many changes will readily suggest themselves without in any way departing from the salient features herein disclosed and embodied in the scope of the claims. 80

What I claim is:—

1. A forming die for flanging the end of a pipe comprising a female die member having a central bore adapted to engage the body portion of the pipe, and a cylindrical recess at the extremity of the bore of larger diameter than said bore and adapted to receive the end of the pipe, a male die member adapted to enter said female die member consisting of a plunger or follower 90 formed with a large cylindrical section and a small end cylindrical extension so constructed and arranged as to permit said small end cylindrical extension to pass through said recess and into the central 95 bore of the female die member and open end of the pipe within the female die member and the large cylindrical section adapted to pass into and be seated in said cylindrical recess, and a removable swivel ring loosely 100 surrounding said small end cylindrical extension and abutting against the adjacent end portion of the large cylindrical section. 105

2. A forming die for flanging the end of a pipe comprising a female die member having a central bore adapted to engage the body portion of the pipe and a cylindrical recess at the extremity of the bore of larger diameter than said bore and adapted to receive the end of the pipe, a male die member adapted to enter said female die member consisting of a plunger or follower formed with a large cylindrical section and a small end cylindrical extension so constructed and arranged as to permit said 110 small end cylindrical extension to pass through said recess and into the central bore of the female die member and open end of the pipe within the female die member and the large cylindrical section adapted to pass into and be seated in said cylindrical recess, and an independent removable swivel ring frusto-conical in shape 115 and loosely surrounding said small end cylindrical extension and abutting against the adjacent end portion of the large cylindrical section. 120

3. A forming die for flanging the end of a pipe comprising a female die member having a central bore adapted to engage the 130

body portion of the pipe and a cylindrical recess at the extremity of the bore of larger diameter than said bore and adapted to receive the end of the pipe, a male die member adapted to enter said female die member consisting of a plunger or follower formed with a large cylindrical section and a small end cylindrical extension so constructed and arranged as to permit said 5 small end cylindrical extension to pass through said recess and into the central bore of the female die member and open end of

the pipe within the female die member and the large cylindrical section adapted to pass into and be seated in said cylindrical recess, 15 and a separate and independent removable swivel ring frusto-conical in shape and loosely surrounding said small end cylindrical extension and having its base abutting against the adjacent end portion of the large 20 cylindrical section.

In testimony whereof I affix my signature.

CHARLES G. CORNELL, JR.
